United States Patent Office

Des. 195,456
Patented June 18, 1963

195,456

BUILDING

August C. Schoenfeld, 45555 Michigan Ave.,
Belleville, Mich.

Filed May 14, 1962, Ser. No. 70,109

Term of patent 14 years

(Cl. D13—1)

FIG. 1 is a front elevational view of a building embodying my new design; and

FIG. 2 is a top plan view.

The rear of the building opposite the front shown in FIG. 1 is of substantially the same appearance as the front thereof except as shown in FIGS. 1 and 2.

I claim:

The ornamental design of a building substantially as shown and described.
